UNITED STATES PATENT OFFICE.

GEORGE COLVIN KENNEDY, OF WATERLOO, IOWA.

MARBLE-GUN.

1,037,262.

Specification of Letters Patent. Patented Sept. 3, 1912.

Application filed November 16, 1911. Serial No. 660,630.

To all whom it may concern:

Be it known that I, GEORGE COLVIN KENNEDY, a citizen of the United States of America, and a resident of Waterloo, Black Hawk county, Iowa, have invented certain new and useful Improvements in Marble-Guns, of which the following is a specification.

My invention relates to improvements in marble-guns, and the objects of my improvements are these: first, to provide a marble-gun with means for correctly sighting it; second, to render such sighting-means foldable over upon the gun to permit the whole to be easily carried in the pocket; third, to adapt the rear sighting means to act as a discharge trigger as well as engaging detachably the propelling means; fourth, to furnish movable pointers on the sighting-means to assist in locating the object aimed at; fifth, to modify the form of the gun to permit it to be seated in a stable position upon the ground, and sixth, to adapt the gun and its said sighting-means to each other so as to permit the sights to fold over upon the gun toward each other, while being prevented from moving in opposite directions beyond the vertical. These objects I have accomplished by the means which are hereinafter described and claimed, and which are illustrated in the accompanying drawings, in which:

Figure 1 is a longitudinal vertical central section through my improved marble-gun, with its propelling-means adjusted for a discharge, the sighting-means shown in full lines in their erect positions and in dotted lines in their folded-over positions. Fig. 2 is a rear elevation of the rear sighting-means, and Fig. 3 is a rear elevation of the forward sighting-means taken on a transverse section of the gun body. Fig. 4 is a horizontal transverse section of the rear sighting-means taken on a line 3—4 of Fig. 2. Fig. 5 is a longitudinal vertical central section through the marble-gun of a modified construction, with the sighting-means shown in both full and dotted lines as in Fig. 1, the propelling-means set for discharge. Fig. 6 is a rear elevation of the rear sighting-means of the gun shown in Fig. 5, and Fig. 7 is a front elevation of the forward sighting means thereof. Fig. 8 is a detailed view of one of the rear corners of the gun-conduit, showing the method

whereby the side standard of the sighting-means is adapted to seat itself thereon to hold such means in either an erect or forwardly-prostrate condition.

60

Similar characters of reference designate corresponding parts throughout the several views.

The gun-body is a tube formed from a suitably shaped metallic blank which is bent over and its longitudinal edges in its middle portion united to produce a hollow cylindrical conduit adapted to receive marbles *l*. The forward part *b* and the rear part *c* of said blank are not united at their longitudinal edges, but by means of a cut in each extending part way from their edges toward the middle line, the blank may be formed into a squared body at each end with vertical walls on each side, the squared bases of these parts *b* and *c* being thus adapted to be in line in the same horizontal plane and therefore provide a secure and stable seat for the gun on the ground or other flat surface.

80

Located partly within the gun-bore and partly in the squared rear channel *c* is a coiled compression-spring *t*, to whose forward end is secured a cylindrical solid head *k* within the gun-bore *a*. Extending rearwardly from the head *k* and secured to it by a nail *s*, and within the hollow of said spring, is a rod *p* which has a finger-piece *p*², and its upper edge is provided with a number of forwardly directed teeth *r*.

90

On the ends of the parts *b* and *c* are located the sighting-means *d* and *m*, alined in the middle longitudinal line of the gun. The rear sight comprises a plate *d* having a medial longitudinal slot *d*², and a movable pointer *e* is slidably seated in said slot, the pointer being formed of a single small piece of metal bent to embrace the edges of the slot. The forward sight *m* is similarly formed but shorter, and has a similar slot *m*² and slideable pointer *n*.

95

The forward sight *m* is pivoted to the forward part or corners of the part *b* above the line of the gun-bore, on a pintle *z*. The part to which this sight is pivoted is projected above the upper edge of the part *b* on each side to form a raised part having a rearwardly-curved edge *b*', over which laterally-projected wings of the sight *m* move with a close-fitting contact. Since the forward part of said projection is angular, the sight when raised to a vertical position, cannot

105

100

110

move forwardly from said position, though it may be swung rearwardly to a prostrate position along the gun *a* as indicated by the dotted lines in Fig. 1. The rear sight *d* is similarly mounted with like lateral wings 5 which engage a similar projection *c'* on each side, the projection serving to permit forward but not rearward swinging of the sight. The rear sight *d* has its lower end 10 divided to form a deep groove *d'* therein, and the divided members thus formed are curved forwardly and pivoted on a pintle *g* to the sides of the part *c*, said pintle also serving as a means of attachment and ful- 15 crum for the rear end of the spring *t*. The inner transverse edge of the groove *d'* in said sight is far enough from the pintle *g* to permit the teeth *r* of the rod *p* to be engaged by it when the sight is brought to its 20 vertical position as shown in Fig. 1. However, the curving of the lower end of the sight changes the relations thereof relative to the rod-teeth *r* so that when the sight *d* is swung forward a little the teeth *r* become 25 disengaged from said sight, which thus becomes a trigger with relation to said rod and spring. In other words, when the rod is drawn forward as much as desired, the sight *d* may be swung to a vertical position 30 engaging the teeth *r*, and may be held in that position until the aim has been adjusted, when the spring *t* may be instantaneously released by merely swinging forward the sight *d* slightly. The plurality of teeth *r* on 35 said rod *p* permits a number of adjustments of the tension of said spring to be made according to the distance necessary to cast the marble *l*. When both sights have been lowered, the compass of the whole gun is small, 40 and it may be easily carried in the pocket of the owner, while if desired, a ring *j* may be slid over the parts to keep them in place.

The device illustrated in Figs. 5 to 8 inclusive employs the same principles of operation generally, but with somewhat varied 45 details of construction. The same gun-body *a*, spring *t*, head *k* are used, but the rod *p'* is formed of a resilient or yieldable rod which is bent upon itself to form a closed 50 loop, the forward end *r'* of the loop being made angular in order to permit it to engage the lower part of the sighting-device *d'* at the rear when the latter is erected to the position shown in Fig. 5, and when the 55 spring has been put under tension. The forward sight *m'* is formed of a loop of wire, about which is slidably seated a looped pointer *n'*. The lower ends of the mem- 60 bers *w* and *x* of the loop *m'* are bent to cross each other, and their extremities are then bent outwardly to pass through orifices in the parts *b*, then bent toward the plane of the loop *m'* and then bent back to cross the vertical edges of the parts *b* when the loop 65 *m'* is erect. The angles of the parts *b* are curved on the arc of a circle whose radius is the distance from the bearing-orifice in the part *b* to the contacting edge of said curved edge with the part crossing it, and the crossed part fits said curved edge closely 70 with rubbing contact. On the upper and vertical edges of said parts *b* are the notches *y* and *o* respectively, and the crossed parts of said looped extremities tend to drop thereinto when in the erect or prostrate po- 75 sition of the forward sight, as indicated in Fig. 5, the springiness of the member tend- 80 ing in each case to retain it in the notch in which it may have been placed. For obvi- 85 ous reasons, the engagement is such, that the part *m'* cannot be displaced forwardly from the vertical position, but it may be easily disengaged from the notch and then brought down to the prostrate position, in which last position it tends to be held by the notch *y*, 90 rendering other retaining-means unneces- 95 sary. The rear sighting-means *d'* is of simi- 100 lar form to the one just described, and its crossed lower extremities similarly engage curved angles of the rear part *c*, and drop into locking notches *h* and *i* when either lowered or raised. The rear sight *d'* has a similar slidable pointer *e'*. The crossed extre- 105 mities *u* and *v* of the rear sight are crossed almost horizontally to provide engaging 110 means for the angle *r'* of the rod *p'*, and the ends of these extremities *f* similarly bind in moving over the curved angles of the parts *c*. When the aim is adjusted, the rod *p'* may be yieldingly bent downward suffi- 115 ciently to clear the crossed extremities *u* and *v* of the rear sight *d'*, and thus the spring *t* is discharged.

It is to be understood that slight variations, or equivalents of the parts described 120 may be adopted in lieu thereof, without departing from the full scope and principles of my invention.

Having described my invention, what I claim as new, and desire to secure by Letters 125 Patent, is:

1. In a marble-gun, in combination, a conduit, an erect sighting-device on said conduit, and propelling-means located at one end of said conduit, said conduit having catches adapted to engage with said sighting-device to detachably secure it in either an erect or a recumbent position.
2. In a marble-gun, in combination, a conduit, an erect sighting-device on each end thereof, and propelling-means located at one end of said conduit, said sighting-devices being adapted to swing in one direc- 130 tion only to move toward each other, said conduit and said sighting-devices having co-acting catches adapted to detachably co- 135 operate for detachably securing said devices to said conduit when the former are prostrated thereupon.
3. In a marble-gun, in combination, a

conduit, and sighting-standards pivoted on its ends in the medial line thereof, said conduit having catches thereon for detachably securing said standards thereto when swung over thereupon.

5 4. In a marble-gun, in combination, a conduit cylindrical in its middle portion and having squared ends with open tops, sighting-standards pivoted to the walls of 70 said open ends, said standards engaging said conduit to prevent movement from the vertical in one direction, but each being adapted to swing toward each other to lie upon the conduit.

10 5. In a marble-gun, in combination, a cylindrical conduit having its ends squared and open at the top, sighting-standards pivoted to the walls of said squared ends and engaging same to prevent movement away 75 from said conduit outwardly, said standards being adapted to fold upon each other and upon the conduit, a driving-head movably seated in said conduit, a spring connected to said driving-head, a rod connected 80 to said driving-head and adapted to be shifted to place said spring under tension, said rod and the rearmost of said standards being adapted to be engaged with each 85 other and then released from each other to 90 secure said spring under tension and then discharge it therefrom.

15 6. In a marble-gun, in combination, a conduit having sighting-standards pivoted to its extremities in its medial longitudinal line, a driving-head movably seated in said conduit, a spring operatively connected thereto, a rod connected to said driving-head and adapted to be shifted to place said 95 spring under tension, said rod having detents on one edge, and the lower part of the rearmost of said sighting-standards being formed to engage detents on said rod when the latter is shifted to place said spring under tension, and to become released from 100 said detents when it is swung forwardly toward said conduit.

20 7. In a marble-gun, in combination, a conduit having its ends notched, and sighting-standards connected to the ends thereof and adapted to be moved toward the conduit to be recumbent thereon and to engage 105 said notches detachably when in that position.

25 8. In a marble-gun, in combination, a conduit, sighting-standards pivoted to the ends thereof and adapted to be swung over thereupon, a driving-head movably seated in said conduit, a spring connected to said driving-head, a finger-piece connected to 110 said driving-head and adapted to be shifted to place said spring under tension, said finger-piece and the rearmost of said sighting-standards being adapted to be engaged together detachably when said spring is under tension.

9. In a marble-gun, in combination, a conduit having its base formed to stand stably on a flat surface, sighting-standards movably connected to the ends thereof and adapted to be moved recumbently thereon from an erect position, a driving-head movably seated in said conduit, a spring connected to said driving-head, a finger-piece connected to said driving-head and adapted to be shifted to place said spring under tension, said finger-piece and the rearmost of said sighting-standards being adapted to be detachably engaged when said spring has been placed under tension.

10. In a marble-gun, in combination, a conduit having portions of its base formed to rest stably on a plane surface, sighting-standards pivoted to the ends of said conduits and having means to prevent their being deflected away from each other beyond vertical lines, a driving-head movably seated in said conduit, a spring operatively connected therewith, a finger-piece connected to said head and having a plurality of engaging-means thereon, the rearmost of said sighting-standards being formed to be engaged with the engaging-means adjustably on said finger-piece when the said spring has been placed under tension to a desired degree and the standard brought to a vertical position.

11. In a marble-gun, in combination, a conduit having sighting-standards pivoted to its extremities, yieldable resilient propelling-means in said conduit, the lower 100 part of the rearmost sighting-standard being so curved from its pivots as to cause it to engage and hold said propelling means when placed erect and when said means are under tension and to become disengaged 105 therefrom when it is tilted forwardly on its pivots.

12. In a marble-gun, in combination, a conduit and a sighting-standard foldably connected thereto, the said standard and conduit having engaging-means co-engaging when the standard is in an erect position to detachably rigidly hold it in that position.

13. In a marble-gun, in combination, a 115 conduit and a sighting-standard foldably connected thereto, the said standard and conduit having engaging-means co-engaging when the standard is in a recumbent position to rigidly hold it in that position.

14. In a marble-gun, in combination, a conduit having resilient propelling-means therein and connected thereto, means for placing said propelling-means under tension, and a sighting-standard on said conduit adapted to be engaged with said propelling-means when the latter is under tension and to become disengaged therefrom to discharge such means when moved in a certain direction.

15. In a marble-gun, in combination, a conduit having its extremities formed to support it stably on a flat surface, resilient propelling-means in said conduit and connected thereto, means for placing said propelling-means under an adjustable tension, and a sighting-standard on said conduit adapted to be moved to lie recumbently upon the conduit, said standard having its lower end formed to engage and detachably hold said propelling-means in an adjusted position.
16. In a marble-gun, in combination, a conduit, and a sighting-standard pivoted thereto near one end and having a projection adapted to yieldingly resiliently engage with the end of said conduit when erect to retain the standard detachably in a vertical position.
17. In a marble-gun, in combination, a conduit, and a sighting-standard pivoted thereto near one end and having a projection adapted to yieldingly resiliently engage with said conduit near its end when recumbent to retain the standard detachably in a recumbent position upon the conduit.
18. In a marble-gun, in combination, a conduit and sighting-standards pivoted thereto near each end, the said standards and conduit having engaging-means co-engaging when the standards are in either an erect or recumbent position, to detachably secure them in those positions.
19. In a marble-gun, in combination, a conduit and sighting-standards pivoted thereto near each end and having projections adapted to detachably co-engage therewith in either an erect or a recumbent position on the conduit, and to be prevented from moving away from each other beyond the erect position when so co-engaged.
20. In a marble-gun, in combination, a conduit, yieldable resilient propelling-means connected to said conduit and movable thereinto, a sighting-standard pivoted to said conduit near said propelling-means and adapted to be detachably engaged with said propelling-means when the latter is in an adjusted state of tension, said standard being adapted to release itself from said propelling-means and discharge the latter when swung forwardly, and said standard being adapted to engage said conduit to engage therewith to prevent its moving rearwardly beyond a vertical position.
21. In a marble-gun, in combination, a conduit, and sighting-standards pivoted within its ends and adapted to fold toward each other to a recumbent position on said conduit, said standard having lateral projections adapted to enter into frictional en-
- gagement with the conduit to secure them in a certain position relative thereto.
22. In a marble-gun, in combination, a conduit formed from a single plate whose middle part is bent over and the edges united in a cylindrical shape with the ends left open at the top and squared to have flat bottoms at the ends and erect side walls, and sighting-standards having their lower ends pivotally connected to the side-walls of said open ends, and adapted to be swung over to lie recumbent upon the cylindrical part of the conduit.
23. In a marble-gun, in combination, a conduit formed from a single plate whose middle part is bent over and the edges united in a cylindrical shape with the ends left open at the top and squared to have flat bottoms at the ends and erect side walls, and yieldable resilient propelling-means within said conduit and connected thereto.
24. In a marble-gun, in combination, a conduit formed from a single plate whose middle part is bent over and its edges united to form a hollow tube, with its end portions left open at the top and ends, sighting-standards erected upon the ends of said tube, and yieldable resilient propelling-means operatively contained within said conduit.
25. In a marble-gun, in combination, a conduit and a sighting-standard foldably connected thereto, the said standard and conduit having engaging-means co-engaging when the standard is in an erect position to detachably rigidly hold it in that position, and an indicating-device adjustably seated upon said standard.
26. In a marble-gun, in combination, a conduit and sighting-standards foldably connected thereto, the said standards and conduit having engaging-means co-engaging when the standards are in either an erect or in a recumbent position to hold them in either of said positions, and indicating-means movably seated upon said standards.
27. In a marble-gun, in combination, a conduit and a sighting-standard foldably connected thereto, said standard and conduit being so formed and adapted as to co-engage and enter into a detachable rigid or relatively fixed connection when the standard is moved into a certain position relative to the conduit.

Signed at Waterloo, Iowa, this 13th day of November, 1911.

GEORGE COLVIN KENNEDY.
